UNITED STATES PATENT OFFICE.

CHARLES HOWARD, OF NEW YORK, N. Y.

PROCESS OF OBTAINING ROSIN AND TURPENTINE FROM WOOD.

1,082,526.

Specification of Letters Patent. Patented Dec. 30, 1913.

Application filed November 3, 1912. Serial No. 730,761.

To all whom it may concern:

Be it known that I, CHARLES HOWARD, a citizen of the United States, residing at New York, N. Y., have invented new and useful Improvements in Processes of Obtaining Rosin and Turpentine from Wood, of which the following is a specification.

This invention relates to obtaining turpentine and other volatile constituents, and also rosin from coniferous wood, particularly from so called "light wood" which consists of stumps of trees which have been cut down for some time. This wood contains a larger amount of rosin and turpentine than do the entire growing trees.

In the accompanying drawing, forming a part of this specification, Figure 1 shows a diagrammatic elevation (partly in section) of a preferred form of apparatus for carrying out my process, and Fig. 2, shows an end view of one of the several storage tanks 17, 21, 28 or 29, showing a glass window therein for observation of the liquids therein, to show how much water is below the turpentine or other oil therein.

The process forming the subject of my invention is preferably carried out in substantially the following manner. Wood of the kind referred to is first chipped, as in pulp making, by being cut across the grain preferably diagonally, in the well known manner. The chips are filled into the basket 1 of a retort 2, and a partial vacuum is then produced in the retort, for example, by connecting the retort 2, with the suction side of the air pump 8, in order to remove the air, as much as possible from the pores of the wood, and from the spaces between the chips. The solvent which preferably consists of turpentine, which may be a light turpentine obtained during a previous operation, is then introduced, preferably under pressure. The mixture of chips and solvent is thereupon heated, for example by introducing steam into the jacket 3 of the retort. In order to accelerate the action of the solvent upon the chips, it is preferable to introduce air into the interior of the body of chips. This may be, and is preferably, hot compressed air, and in order to give better agitation it is introduced through the roses 4, in a downward direction. During this treatment with air, the pressure in the receptacle is allowed to rise more or less in order to prevent evaporation of the solvent as much as possible, and

also in order that the solvent will thoroughly permeate each chip and extract the rosin therefrom as thoroughly as possible. By proper manipulation of the valve 3^a the pressure may be caused to fluctuate in the retort 2, for example by gradually raising and lowering the pressure between atmospheric pressure and a pressure of about 30 pounds pressure above atmospheric. By thus causing the pressure to fluctuate, the solvent very thoroughly extracts the soluble matter from the chips. The steam for heating the retort is supplied from the boiler 5, through the steam main, and valved connection 6. The steam exhaust of the jacket is illustrated at 7. The compressed air from the compressor 8 passes through a vessel 9, where moisture separates out as water, thence through pipe 10, air heater 11, pipes 12 and 13 into the pipe 14, and out through the roses 4. The pipe 14 makes a more or less tight joint with the pipe 13, both being suitably tapered at their ends, for this purpose. The air passing through the solvent and chips, carries off more or less of the solvent, as vapor, which is condensed in the coil 15, and passes through separator 16 into the storage receptacle 17. This may be pumped back, by pump 18 and pipe 19 into the retort 2.

When the solvent has extracted as much as possible from the chips, it is drawn off through pipe 20, into tank 21, and the chips may be treated if necessary, or if desired with a second volume of solvent in order to more completely extract the rosin. This treatment will be carried out in substantially the same manner as the treatment above referred to, and this second solution will preferably be drawn off separate from the first or stronger solution, and may be used for treating a fresh batch of chips, thus making the extraction systematic. The chips within the retort 2 are thereupon treated with live steam in order to distil turpentine or other solvent from the chips as completely as possible and during this treatment with steam the retort may also be heated by introducing live steam, or other heating fluid into the jacket of the retort. The solution of rosin in turpentine or other solvent is distilled in the still 22, preferably while introducing both a current of air through pipe 23, and rose 24 into the bottom of the still and a small amount of water through rose 25, into the material

being distilled in order to prevent overheating of this material which would injuriously affect the same. The rosin is drawn off from this still through pipe 26, 5 and is then cooled and thereby solidified, being then ready for packing and shipment. The vapors leaving the still pass through the condenser 27, thence through separator 28, into storage tank 29. From said tank 10 a part of the turpentine may be pumped back into storage tank 17 through pipe 31 for use as a solvent, in treating more chips and the remainder drawn off for shipment.

By means of this process I can obtain a 15 maximum yield of both turpentine and rosin from the wood, with a minimum of labor and expense. The chips after being thus thoroughly extracted are especially suitable for use in paper or pulp making and constitute a valuable by-product.

In the appended claims, the expression "untreated wood" means wood of the coniferous trees, carrying turpentine, rosin or similar substances, which have not been 25 treated with steam or solvents.

The expression "commminuted condition" is intended to include chips, sawdust and similar forms, as distinguished from boards or logs.

30 What I claim is:—

1. A process of extracting the resinous component of comminuted, coniferous wood, which comprises acting upon the untreated wood with a solvent for said resinous bodies, agitating said solvent while in contact with said wood by introducing a plurality of streams of heated air, in a downward direction, and withdrawing said solvent, with the material dissolved therein at the 40 end of said extraction.

2. A process of obtaining rosin and vola-

tile constituents from coniferous wood, which comprises subjecting said wood in a comminuted condition, to the action of a vacuum, then, to the action of a solvent of 45 rosin, and alternately increasing and decreasing the fluid pressure in the treating vessel during the action of said solvent.

3. A process of obtaining resin and volatile constituents from coniferous wood, 50 which comprises acting upon untreated wood in a comminuted condition, with a solvent of rosin, and varying the fluid pressure in the treating vessel during the action of said solvent.

4. A process of extracting rosin and other constituents from untreated, comminuted, coniferous wood, which comprises removing the air from the interstices of said wood by the action of a vacuum, then acting upon 60 said wood with a solvent of rosin under pressure, agitating the mixture of air and solvent by introducing air under pressure, and varying the pressure within the extracting vessel during said extraction step. 65

5. A process of obtaining rosin and turpentine from wood containing the same, which process comprises treating the untreated wood in a subdivided condition, with turpentine under pressure to obtain an extract of resinous constituents in turpentine, agitating said turpentine during said treatment, and causing the fluid pressure within the treating vessel to alternately rise and fall during said treatment. 70

Signed at Washington, D. C. this eighth 75 day of November, A. D. 1912.

CHARLES HOWARD.
